(57) **CLAIM**

The ornamental design for an outer shaft for a targeting device for minimally invasive surgery, as shown and described.

DESCRIPTION

FIG. 1 is a front perspective view of an outer shaft for a targeting device for minimally invasive surgery;

FIG. 2 is a rear perspective view of the outer shaft for a targeting device for minimally invasive surgery shown in FIG. 1;

FIG. 3 is a lateral elevation view of the outer shaft for a targeting device for minimally invasive surgery shown in FIG. 1;

FIG. 4 is another lateral elevation view of the outer shaft for a targeting device for minimally invasive surgery shown in FIG. 1;

FIG. 5 is yet another lateral elevation view of the outer shaft for a targeting device for minimally invasive surgery as shown in FIG. 1;

FIG. 6 is a front elevation view of the outer shaft for a targeting device for minimally invasive surgery as shown in FIG. 1; and,

FIG. 7 is a rear elevation view of the outer shaft for a targeting device for minimally invasive surgery as shown in FIG. 1.
